CLAIM

The ornamental design for a display device with stylized logo as shown and described.

DESCRIPTION

The patent or application file contains at least one drawing executed in color. Copies of this patent with color drawings will be provided by the Office upon request and payment of the necessary fee.

FIG. 1 is a front view of a first embodiment of a display device with stylized logo, showing our new design;

FIG. 2 is a front view of a second embodiment of a display device with stylized logo, showing our new design;

FIG. 3 is a front view of a third embodiment of a display device with stylized logo, showing our new design;

FIG. 4 is a front view of a fourth embodiment of a display device with stylized logo, showing our new design; and,

FIG. 5 is a front view of a fifth embodiment of a display device with stylized logo, showing our new design.

The outermost broken lines in FIG. 5 illustrate an exemplary display device and form no part of the claimed design. The remaining broken lines in FIG. 5 illustrate portions of the display screen of the display device and portions of a graphical user interface on the display device and form no part of the claimed device. The shading depicts a contrast in appearance of the claimed design.

It is certified that error appears in the above-identified patent and that said Letters Patent is hereby corrected as shown below:

On the Title Page

Under item (57), DESCRIPTION, Right Column, Line 20, correct “part of the claimed device. The shading depicts...” to read --part of the claimed device. The dot-dash boundary line in FIGS. 1-5 illustrates the periphery of the embodiment drawing view of a display portion and forms no part of the claimed design. The shading depicts....--
